UNITED STATES PATENT OFFICE.

WILLIAM R. MAXWELL, OF WAKEFIELD, PENNSYLVANIA.

POLE-COUPING.

SPECIFICATION forming part of Letters Patent No. 444,247, dated January 6, 1891.

Application filed June 28, 1890. Serial No. 357,100. (No model.)

To all whom it may concern:

Be it known that I, WILLIAM R. MAXWELL, a citizen of the United States, residing at Wakefield, in the county of Lancaster and State of Pennsylvania, have invented a new and useful Pole-Coupling, of which the following is a specification.

The invention relates to improvements in pole-couplings.

10 The object of the present invention is to provide a simple and inexpensive pole-coupling capable of ready adjustment to adapt the pole to various-sized vehicles.

The invention consists in the construction and novel combination and arrangement of parts hereinafter fully described, illustrated in the accompanying drawings, and pointed out in the claim hereto appended.

In the drawings, Figure 1 is a perspective view of a tongue provided with couplings constructed in accordance with this invention. Fig. 2 is a plan view. Fig. 3 is a detail sectional view.

Referring to the drawings, 1 designates a vehicle pole or tongue of ordinary construction, having secured to its rear end a curved cross-bar that is centrally secured to the pole or tongue and is braced by side bars 3, which extend from the tongue to the end of the curved cross-bar. The ends of the curved cross-bar 2 are provided with brackets 4, which are composed of a plate 5, a cross-bar 6, formed integral with the plate, and a curved brace 7, having one end bolted to the plate 5 and the other end perforated and adapted for the reception of the end 8 of the cross-bar 6, which end is reduced and secured in the perforation of the brace. The portion 9 of the plate 5, extending rearward of the curved cross-piece, is curved similarly to the curved brace, and the cross-bar extends inward from the plate at right angles to the tongue and is approximately V-shaped in cross-section and has sliding upon it a coupling-block 10, provided at one end with an

eye 11 and at the other end with a V-shaped opening 12, extending transversely across the block and adapted to receive the cross-bar 6.

The coupling-block 10 is capable of lateral adjustment along the cross-bar 6 to adapt the tongue or pole to various-sized vehicles, and the V-shaped cross-bar and the similar opening of the coupling-blocks prevent the latter swinging upon the cross-bar, and in order to retain the coupling-block at any desired point of adjustment is provided with a set-screw 13, arranged to engage the front face of the cross-bar.

It will readily be seen that the pole-coupling is simple and inexpensive in construction, and is capable of a ready adjustment to adapt the tongue to various-sized vehicles.

From the foregoing description and the accompanying drawings the construction, operation, and advantages of the invention will be readily understood.

What I claim is—

A thill-coupling comprising the bracket 4, consisting of the plate 5, adapted to be secured to the curved cross-bar 2 and having the curved portion 9, the cross-bar formed integral with the plate 5 and extending at right angles to the tongue or pole and being approximately V-shaped in cross-section, the curved brace 7, having one end secured to the plate 5 and the other end perforated and receiving the end of the cross-bar, and the coupling-block 10, being laterally adjustable along the cross-bar and having at one end the eye 11 and at the other end the V-shaped opening to receive the cross-bar and provided with a set-screw arranged to engage the cross-bar, substantially as described.

In testimony that I claim the foregoing as my own I have hereto affixed my signature in presence of two witnesses.

WILLIAM R. MAXWELL.
